UNITED STATES PATENT OFFICE.

CHARLES EDGAR KNAPP, OF NEW YORK, N. Y.

DESIGN FOR A RUBBER BINDING.

No. 38,095.

Specification for Design.

Patented June 19, 1906.

Application filed April 20, 1906. Serial No. 312,921. Term of patent 14 years.

To all whom it may concern:

Be it known that I, CHARLES EDGAR KNAPP, a citizen of the United States, residing at No. 900 Union street, borough of Brooklyn, city and State of New York, have invented a new, original, and ornamental Design for Rubber Bindings, of which the following is a specification, reference being had to the accompanying drawing, forming part thereof.

The figure is a semiperspective view of the binding, showing my design.

I claim—

The ornamental design for rubber binding, as shown.

CHARLES EDGAR KNAPP.
